AEROSOL DISPENSER

Robert M. Montague, Winston-Salem, N.C., assignor to Paramedical Research and Development Corporation,
Winston-Salem, N.C., a corporation of North Carolina

Filed Mar. 28, 1969, Ser. No. 16,513

Term of patent 14 years

Int. Cl. D23—04; D15—02

U.S. Cl. D23—148

FIG. 4

FIG. 1

FIG. 2

FIG. 1 is a side perspective view of an aerosol dispenser embodying my design;

FIG. 2 is a side elevational view of FIG. 1;

FIG. 3 is a front elevational view of FIG. 1; and

FIG. 4 is a top plan view of FIGS. 2 and 3.

The aerosol dispenser is fragmentarily shown in FIGS. 2 and 3 for convenience of illustration.

I claim:

The ornamental design for an aerosol dispenser, as shown and described.
